UNITED STATES PATENT OFFICE

127,507

DESIGN FOR AN ELECTRIC IRON HANDLE

William J. Russell, Mansfield, Ohio, assignor to
Westinghouse Electric & Manufacturing Company,
a corporation of Pennsylvania

Application February 26, 1941, Serial No. 99,215

Term of patent 14 years

To all whom it may concern:

Be it known that I, William J. Russell, a citizen of the United States, residing at Mansfield, in the county of Richland and State of Ohio, have invented a new, original, and ornamental Design for an Electric Iron Handle, of which the following is a specification, reference being had to the accompanying drawing, forming part thereof, in which:

Figure 1 is a perspective view taken from above and to one side of an electric iron handle showing my new design;

Fig. 2 is a perspective view taken from above and towards the rear of the same; and

Fig. 3 is a top plan view of the same.

The characteristic feature of my design resides in the top longitudinally-extending portion of the handle, together with the merging thereof into the upright portions at the front and rear.

I claim:

The ornamental design for an electric iron handle, substantially as shown and described.

WILLIAM J. RUSSELL.
